UNITED STATES PATENT OFFICE.

JOSEPH O. MAUBORGNE, OF CHICAGO, ILLINOIS, AND LOUIS COHEN, OF WASHINGTON,
DISTRICT OF COLUMBIA.

ELECTRICAL SIGNALING.

Application filed July 28, 1922. Serial No. 577,664.

To all whom it may concern:

Be it known that we, JOSEPH O. MAUBORGNE and LOUIS COHEN, citizens of the United States, residing at Chicago, in the county of Cook, State of Illinois, and Washington, District of Columbia, respectively, have invented certain new and useful Improvements in Electrical Signaling, of which the following is a specification.

10 This invention relates in general to the art of radio signaling, and more particularly to the receiving of radio signals, and a system for use in practising the same.

15 The object of the present invention is to eliminate electrostatic disturbances and other interferences in the reception of radio signals and thus improve the clearness and reliability of radio communication.

20 In pending application, Serial Number 440,203, filed January 26, 1921, we have described a method for receiving radio signals in which resonance wave coils are employed and for utilizing the wave development effects produced by electrical oscillations acting 25 on the antenna. The present invention is another modification of the same general idea embodying some additional features which are novel and useful in securing still greater improvements in the results desired, 30 viz., more effective elimination of static disturbances and other interferences in the reception of radio signals.

35 In view of the fact that the underlying principles of the present invention are the same as those utilized in the pending application referred to above, and also in the pending applications, Serial Numbers 401,752 and 419,383, it is not deemed necessary to repeat here the discussion of the basic principles 40 governing its operation. We shall limit the description to the novel features introduced in the present invention, and this can be more readily understood by reference to the accompanying diagrams showing typical 45 embodiments of the invention, and which form part of the specification.

In the accompanying drawings:-

50 Figure 1 is a diagrammatic view of the invention in which the antenna is connected in series with a loop circuit, and the wave coil connected to the antenna circuit either above or below the loop circuit.

In Figure 2 an additional intermediate

circuit is introduced between the detector circuit and the metal ring which forms an electrostatic connection to the wave coil.

55 Another embodiment of our invention is shown in Figure 3 in which a loop antenna circuit is employed, grounded at one end, and the wave coil connected to the grounded end of the loop circuit.

60 Figure 4 is a modification of Figure 3 which consists in introducing a loop circuit between the antenna and ground.

65 Another modification of our invention is shown in Figure 5 which is similar to Figure 3 except that an additional metal tube, grounded through a loop circuit, is used.

70 The arrangement shown in Figure 6 is similar to that of Figure 4 except that an additional metal tube, grounded through a loop circuit, is used.

75 Having more particular reference to the drawings, and in connection with which like characters of reference will designate corresponding parts thereof, in Figure 1 the antenna 1 is connected to a loop circuit which consists of an inductance 2, and a condenser 3 connected in parallel, the other terminal of the loop circuit being grounded at 4.

80 The circuit 1, 2, 3, 4, constitutes the antenna circuit. The wave coil 5 is connected to the antenna circuit, the connection being made either at the point 20, that is at a point above the loop circuit, or at the point 85 6, at the grounded end of the loop circuit.

This is accomplished by changing the switch connection 21 from point 22 to point 23. Part of the wave coil 5 is enclosed in the metal tube 7 which is grounded at the point 90

85 8 through a separate loop circuit consisting of an inductance 9 and condenser 10 connected in multiple. The ring 11 constitutes an electrostatic connection between the wave coil 5 and the oscillating circuit 12-13, the detector being connected across the terminals of condenser 13. The principles of operation 95 covering this circuit arrangement have already been fully discussed in the pending applications referred to above. It is to be

100 noted that the improvement effected by this invention consists in the introduction of an additional loop circuit 2, 3, in the antenna circuit. It was found by experiment that the introduction of an additional loop circuit, 2, 3, in the antenna circuit offers a still

105

further improvement in the elimination of static and other interference. This is particularly marked when the wave coil 5 is connected to the point 6 at the grounded end 5 of the loop circuit.

The arrangement shown in Figure 2 differs from that shown in Figure 1 only in the introduction of an additional tuned circuit between the detector circuit 12, 13 and 10 the ring 11. The ring 11 is in this case connected to a circuit consisting of condensers 14, 16 and an inductance 15. This circuit 14, 15, 16, is coupled to the detector circuit 12, 13.

15 In Figure 3 an arrangement is shown in which a loop antenna 17 is used, the loop antenna being closed through a condenser 18 and grounded at 19. The wave coil 5 is connected at the point 6, which is the grounded 20 end of the loop antenna circuit. In this case we also have an intermediate circuit, 14, 15, 16, between the detector circuit proper 12, 13, and the ring 11, which constitutes the electrostatic connection to the wave coil.

25 The modification shown in Figure 4 differs from that shown in Figure 3 only in that an additional loop circuit consisting of an inductance 2 and capacity 3 joined in parallel is interposed between the loop antenna 17, 18, and the ground 19. In this case we also have a switch 21 for the purpose of connecting the wave coil either to a point 20 or point 6, that is to a point above the loop circuit or to a point below 35 the loop circuit.

Still another modification is shown in Figure 5 which is similar to Figure 3 except that a metal tube 7, grounded at 8 through loop circuit 9, 10, is used.

40 Figure 6 is a modification of Figure 4 having the additional feature of a metal tube 7, grounded at 8, through loop circuit 9, 10.

Claims:

45 1. In a system for the reception of radio signals, the combination of an antenna, a loop circuit and ground constituting an antenna circuit, a wave coil connected to the junction point of the antenna and loop circuit, part of said wave coil being enclosed in a metal tube, said metal tube being grounded through an independent loop circuit, said wave coil being also electrically connected to a detector through an oscillating circuit.

50 2. In a system for the reception of radio signals, the combination of an antenna, loop circuit and ground constituting an antenna circuit, a wave coil and a switching arrangement for connecting said wave coil either to a point above the loop circuit or to a point below the loop circuit of the antenna circuit, said wave coil being enclosed in a metal tube, said metal tube being 55 grounded through an independent loop circuit,

circuit, a detector being connected across an oscillating circuit, said oscillating circuit being electrostatically connected to the said wave coil.

3. In a system for the reception of radio 70 signals, the combination of an antenna, loop circuit and ground constituting an antenna circuit, a wave coil and a switching arrangement for connecting said wave coil either to a point above the loop circuit or to a point below the loop circuit of the antenna circuit, said wave coil being enclosed in a metal tube, said metal tube being grounded through an independent loop circuit, a detector being connected across an oscillating circuit, said oscillating circuit being electrostatically connected to the said wave coil through a metal ring, 75 said metal ring being slideable along the wave coil.

4. In a system for the reception of radio signals, the combination of an antenna, loop circuit and ground constituting an antenna circuit, a wave coil and a switching arrangement for connecting said wave coil either to a point above the loop circuit or to a point below the loop circuit of the antenna circuit, said wave coil being enclosed in a metal tube, said metal tube being grounded through an independent loop circuit, a detector associated with said wave coil through two oscillating circuits in electrical relation to each other, the detector being connected to one of said oscillating circuits, and the other of said oscillating circuits being connected through a metal ring which is slideable along the wave coil; said metal ring constituting an electrostatic connection between the wave coil and detector circuits. 90

5. In a system for receiving radio signals 105 the combination of a loop antenna, said loop antenna being closed through a condenser and one end of said condenser being grounded, a wave coil connected to the grounded end of said loop antenna and a detector electrically associated with said wave coil through two oscillating circuits which are electrically coupled, the detector being connected to one of said oscillating circuits and the other of said oscillating circuits being connected electrically to the said wave coil.

6. In a system for receiving radio signals 110 the combination of a loop antenna, said loop antenna being closed through a condenser and one end of said condenser being grounded, a wave coil connected to the grounded end of said loop antenna and a detector electrically associated with said wave coil through two oscillating circuits which are electrically coupled, the detector being connected to one of said oscillating circuits and the other of said oscillating circuits being connected electrostatically 115 through a metal ring to the said wave coil. 120

7. In a system for receiving radio signals, the combination of a loop antenna, said loop antenna being closed through a condenser, a loop circuit interposed between said loop antenna circuit and ground, a wave coil connected to said loop antenna circuit and a detector associated electrically with said wave coil through two oscillating circuits, said oscillation circuits being coupled electrically. 40
8. In a system for receiving radio signals, the combination of a loop antenna, said loop antenna being closed through a condenser, a loop circuit interposed between said loop antenna circuit and ground, a wave coil and a switching arrangement for connecting the wave coil to the loop antenna circuit either to a point above the antenna loop circuit or to a point below the antenna loop circuit, a detector associated electrically with said wave coil through two oscillating circuits, said two oscillating circuits being electrically coupled. 45
9. In a system for receiving radio signals, the combination of a loop antenna, said loop antenna being closed through a condenser, a loop circuit interposed between said loop antenna circuit and ground, a wave coil and a switching arrangement for connecting the wave coil to the loop antenna circuit either to a point above the antenna loop circuit or to a point below the antenna loop circuit, a detector being electrically associated with said wave coil through two oscillating circuits, said two oscillating circuits being electrically coupled, said detector being connected to one of said oscillating circuits, and the other of said oscillating circuits being connected electrostatically to the wave coil through a metal ring. 50
10. In a system for receiving radio signals, a combination of a loop antenna, said loop antenna being closed through a condenser, one terminal of said condenser being grounded, a wave coil connected to the grounded terminal of said loop antenna circuit, part of said wave coil being enclosed in a metal tube, said metal tube being grounded through a separate loop circuit, a detector electrically associated with said wave coil through two oscillating circuits, said two oscillating circuits being electrically coupled, the said detector being connected across the terminals of one of said oscillating circuits, the other of said oscillating circuits being connected electrostatically to the said wave coil. 55
11. In a system for receiving radio signals, the combination of a loop antenna, said loop antenna being closed through a condenser, one terminal of said condenser being grounded through a loop circuit, a wave coil and a switching arrangement for connecting said wave coil to the loop antenna circuit either to a point above the loop circuit or to a point below the said loop circuit, a metal tube enclosing part of said wave coil, said metal tube being grounded through an independent loop circuit, a detector associated electrically through two oscillating circuits with said wave coil, the said two oscillating circuits being electrically coupled. 60
